F. H. LAMB

DETACHABLE CONVEYER BUCKET

Filed Dec. 4, 1923

By

Paul D. Breyer Attorney

UNITED STATES PATENT OFFICE.

FRANK H. LAMB, OF HOQUIAM, WASHINGTON.

DETACHABLE CONVEYER BUCKET.

Application filed December 4, 1923. Serial No. 678,421.

To all whom it may concern:

Be it known that I, FRANK H. LAMB, a citizen of the United States, residing at Hoquiam, in the county of Grays Harbor 5 and State of Washington, have invented certain new and useful Improvements in Detachable Conveyer Buckets, of which the following is a specification, reference being had therein to the accompanying drawings.

10 This invention relates to certain new and useful improvements in detachable conveyer buckets for handling conveyers and the like, the object being to provide a bucket which is formed of two sections so constructed that it can be placed in position on any round link conveyer chain or removed therefrom.

Another and further object of the invention is to provide a detachable conveyer 20 bucket which is so constructed that it will be securely held in its proper position on the conveyer chain after being attached.

Another and further object of the invention is to provide a detachable conveyer 25 bucket which is exceedingly simple and cheap to manufacture, the parts being so formed and connected together that the sections are clamped over the conveyer chain in such a manner that all danger of the bucket becoming detached when in use is prevented.

Other and further objects and advantages of the invention will be hereinafter set forth and the novel features thereof defined by the 35 appended claims.

In the drawings,

Figure 1 is a perspective view of my improved construction of conveyer bucket showing it in position on a chain in dotted 40 lines;

Figure 2 is a longitudinal section through the same; and

Figure 3 is a top plan view showing the chain in section.

45 In carrying out my invention I form the bucket of two scoop-shaped sections 1 and 2, the scoop shaped section 2 being provided with a tapering shank 3 which is adapted to extend between the inwardly box shaped portions 4 and 5 of the section 1, the walls of the box shaped portions 4 and 5 being provided with openings in transverse align-

ment adapted to register with openings formed in the shank 3 and through which bolts 6 are adapted to be passed carrying 55 nuts 7 for locking the shank in position within the section 1.

The bottom of the section 1 is provided with a lug 8 adapted to extend into a notch 9 formed in the shank 3. The adjacent ends 60 of the sections 1 and 2 are rounded as clearly shown to receive the chain, and it will be readily seen that the shank 3 of the section 2 can be forced through a link of an ordinary round chain and when clamped in position 65 within the section 1, the bucket will be clamped in position on the conveyer chain.

I am aware that various changes can be made in the details of construction as herein shown as for instance the adjacent ends of 70 the sections 1 and 2 could be so shaped to receive a chain having a different contour than that herein shown and therefore I do not wish to limit myself to any of these details of construction as my invention 75 consists broadly in providing a detachable conveyer bucket formed of two sections, one section being provided with a shank adapted to pass through a link in a conveyer chain and be secured within the other section by 80 bolts or rivets extending transversely through the section and shank.

From the foregoing description it will be seen that I have provided a detachable conveyer bucket especially adapted to be used in connection with any of the well known round link conveyer chains now in use, one of the sections being provided with a tongue or shank adapted to pass through the link of the chain so that the two sections when 90 united will be clamped on the link of the chain as clearly shown and in such a manner that the bucket can be easily and quickly attached or detached.

What I claim is:—

1. A conveyer bucket formed of two scoop like sections, one section being provided with inwardly extending box like portions and the other section being provided with a shank adapted to fit between said box like 100 portions, said shank and box like portions being provided with registering openings and bolts extending through said openings for securing said sections together.

2. A detachable conveyer bucket for conveyer chains composed of two scoop like bucket sections, one section being provided with a shank and the other with a portion adapted to receive said shank, a lug formed on the bottom of the last mentioned section, a notch formed in said shank adapted to engage said lug and bolts adapted to pass transversely through the shank and section for securing said sections in position on a 10 conveyer chain.
- In testimony whereof I hereunto affix my signature.

FRANK H. LAMB.
